UNITED STATES PATENT OFFICE.

JAY G. ROBINSON, OF CHICAGO, ILLINOIS.

DOOR-OPERATING MECHANISM.

Application filed June 16, 1924. Serial No. 720,185.

My invention is an improvement in pneumatically-operated doors for locomotive fire boxes, certain features of the invention being applicable, however, to doors used for other purposes and to moving parts other than doors. One of the objects of the invention is to provide improved means for retarding the movement of a door near the limits of its movement, thereby bringing it to rest without shock. Another object when two doors are employed, one moving upwardly when the other moves downwardly, is to so connect the doors by pivoted members that each substantially counteracts the weight of the other in such manner that the retardation of each door is communicated to the other. Another and important object is to produce retardation of the door movement near the limits thereof by the action of the pivotal members by which the doors are operated and connected, thus obviating the necessity of relying for the cushioning effect exclusively upon the compression of air in the pneumatic operating mechanism.

Other objects will appear in the following description of the particular structure in which I have embodied the invention in the mechanism shown in the accompanying drawings, in which—

Figure 1 is a front elevation of a locomotive fire box door embodying my invention with the doors in closed position.

Figure 2 is an end elevation from the left-hand side of the structure shown in Figure 1.

Figure 3 is an end view from the right-hand side of the structure shown in Figure 1.

Figure 4 is a front elevation similar to Figure 1, but showing the doors in open position.

Figure 5 is a longitudinal sectional view of the pneumatic operating cylinder.

Figure 6 is an outline diagram in which the movement of the doors and of their operating and connecting members is plotted.

The pneumatic operated mechanism illustrated herein is of the type described and claimed in United States Letters Patent No. 922,530, granted to F. Shoemaker, May 25, 1909, and in my Patents Nos. 1,492,896, granted May 6, 1924, and 1,325,657, granted December 23, 1919, respectively.

The door opening is surrounded and defined by a frame 1 to which the doors 4 and 5 are pivoted at 2 and 3, the doors being designed to meet in closed position along

a substantially horizontal line α about midway of the door opening and to move toward and away from each other in a substantially vertical plane in closing and opening respectively. The two door operating levers 6 and 7 are pivoted to the door frame at 8 and 9 respectively. Links 10 and 11 are pivoted to levers 6 and 7 at 12 and 13 respectively, and at their opposite ends these links are pivoted at 14 and 15 to the doors 4 and 5 respectively. The levers 6 and 7 are connected by a link 16. The link 16 is pivoted to the lever 7 at 18, the lever fulcrum 9 being between the pivots 13 and 18. The pivotal connection 17 of the link 16 with lever 6 is between the fulcrum 8 of that lever and the pivot 12.

The lever 6 extends beyond the pivot 12 as shown at 19, the part 19 serving as an operating handle when the door is operated manually. The lever 7 has an arm 20 projecting upwardly and pivoted at 20' to the link 21, which at its opposite end is pivoted at 22 to the piston rod 23 of the pneumatic operating cylinder which is designated generally by the numeral 24.

The doors are opened and closed by the inward and outward movement of the piston rod 23 operating in the cylinder 24. The outward movement of the piston rod 23, that is its movement toward the left as viewed in the drawings, rotates the lever 7 upon its pivot 9 in counter-clockwise direction, thus imparting an upward thrust to the link 11 and upper door 5. The counter-clockwise movement of the lever 7 also imposes a downward thrust upon the link 16 which in turn is transmitted to the lever 6, and through the link 10 to the lower door 4. The result, therefore, of the movement of the piston rod 23 to the left is to raise the upper door 5 and to lower the lower door 4, thereby moving them to the open position shown in Figure 4. Upon the reverse movement of the piston rod 23 toward the right, as viewed in the drawings, the forces are transmitted in the same way but in the opposite direction, thereby causing the doors to close.

It will be observed that I have placed the operating cylinder 24 above the door opening and spaced outwardly sufficiently from the door frame 1 to permit the upper door 5 to pass between it and the door frame.

The construction of the cylinder 24 and its operation are as described in the prior

patents to Shoemaker and to myself above referred to, and a brief description thereof will suffice for the purposes of this specification. As shown in Figure 5, the cylinder is provided with two auxiliary aligned bores 25 and 26 of different diameter, and the piston rod 23 has secured thereto a large piston 27 fitting the larger bore 25, and a smaller piston 28 fitting the smaller bore 26. These pistons are provided with the usual rings 29-30, and cup leathers 31-32. Fluid under pressure, compressed air being used for the operation of fire-box doors upon locomotives, is supplied through the pipe 35. Referring now to Figure 5, the pipe 35 is connected by a T-coupling 35' to an opening in the side of the cylinder 24, which opening is the entrance to a duct leading to the end of the large bore 25 immediately adjacent its junction with the small bore 26. This duct extends inwardly, as indicated at 38, thence parallel to the axis of the cylinder as indicated at 39, and thence in the opposite direction parallel to the axis of the cylinder as indicated at 40, a right angular extension 41 at the inner end of the part 40 leading the duct to the larger bore 25 adjacent its junction with the small bore. At the junction of the parts 39 and 40 of this duct, I provide an inwardly opening check-valve 42, and in the part 41 of the duct adjacent its point of communication with the large bore 25, I provide a three-way valve 43. In the position of the valve 43 illustrated in Figure 5, its through bore 44 establishes continuity of the duct and communication between the large bore 25 and the pipe 35. When the valve 43 is rotated ninety degrees clockwise communication is established between the radial bore 45 of the valve and the large bore 25 and thence through the bore 44 to the atmosphere at 46.

During the pneumatic operation of the doors, the valve 43 always remains in the position shown in Figure 5, being moved from that position only for a special purpose to be hereinafter described, and the space 25 between the large and small pistons is, therefore, in constant communication through the pipe 35 with the source of air pressure.

The pipe 35 beyond the point 35' where it communicates with the space between the pistons extends over the top of the door opening and down at the side thereof to a valve 36 which may be of the type shown in the Robinson and Shoemaker patents above referred to. As my present invention involves no novelty in the construction of this valve, I will here simply describe the functions which it performs. The valve is operated by a foot-treadle 37. When the treadle is in its normal position, i. e., its elevated position, the valve closes the port in the valve casing with which pipe 35 communicates

and prevents the flow of air from pipe 35 to pipe 34, pipe 34 in this position of the treadle and valve being in communication with the atmosphere through an exhaust opening in the valve casing. When the valve is moved by depressing the treadle the pipe 34 is cut off from the exhaust opening and placed in communication with the pipe 35 permitting the flow of air from pipe 35 through pipe 34 to the outer side of the large piston through the duct 46 shown in Figure 5.

The duct 46 is provided with two branches 60 and 61. The branch 60 communicates with the cylinder through its side wall at a point adjacent the outer or right-hand end thereof as viewed in Figure 5, and the branch 61 communicates with the cylinder through its end wall. In the branch 61, I provide an inwardly opening check-valve 47 which is by-passed by a minute bleed opening 48, which bleed opening I have shown as extending directly through the body of the valve 47. In operation, assuming that the doors are closed and the pistons 27, 28, at their extreme right-hand position as viewed in Figure 5, depression of the treadle 37 establishes communication between the air supply pipe 35 and the pipe 34, thereby admitting pressure through the duct 46 and branch 61 to the outer side of the large piston 27. The space between the pistons 27 and 28 is constantly in communication with the source of compressed air through the pipe 35 as above explained, this constant pressure of air between the large and small pistons never being interrupted during the pneumatic operation of the doors. When pressure is admitted on the outer side of the large piston 27 by depression of the treadle as above described the two pistons with the piston rod 23 to which they are connected move to the left. This movement is due to the fact that the pressure of air upon the small piston 28 and upon the outer side of the large piston 27 overcomes the pressure acting in the opposite direction upon the inner side of the piston 27, it being understood that the space upon the outer side 49 of the small piston is in communication with the atmosphere. In the conditions described, therefore, the air pressure acting to move the pistons to the left is effective upon a greater area, namely the area of one side of the large piston plus one side of the small piston, while the pressure acting to move the pistons to the right is effective only upon one side of the large piston. The effective effort of the air pressure, therefore, is that due to the area of one side of the small piston. As the pistons move to the left the check-valve 39 prevents escape of air from the space between the pistons, and as this body of air is moved by the movement of the pistons from the

large bore 25 to the small bore 26, it is subjected to increased pressure; that is, to pressure higher than that of the supply of compressed air admitted through the pipe 35. The rise in pressure of this body of air confined between the two pistons progressively increases the resistance to their movement, and when the pistons have reached the end of their stroke toward the left, the pressure of the confined body of air has risen to a point sufficient to retard the movement of the pistons and bring them to rest without shock. It will be observed, however, that the cushioning effect so obtained is dependent upon the air between the two pistons being confined in that space, but in practice difficulty is sometimes experienced in maintaining the cup leathers 31, 32, and rings 29, 30, in sufficiently perfect condition to confine the body of air between the pistons to an extent sufficient to produce a perfect cushioning effect. To improve this cushioning effect is one of the objects of the invention claimed herein, the operation above described being that which has previously been in use as described in the prior patents hereinbefore referred to.

Upon reference to Figure 1, it will be observed that the links 10, 11, extend approximately at right angles to the levers, 6, 7, when the doors are in closed position, and by reference to Figure 4, it will be observed that during the opening movement of the doors the links rotate, the link 11 counter-clockwise and the link 10 clockwise, upon their pivotal connections 13 and 12 with the levers 7 and 6, respectively. When the doors have reached their fully open position the link 11 has rotated almost into alignment with the lever 7 and the link 10 has rotated into alignment with the lever 6. In Figure 6, I have shown the movement of the levers and links plotted in closed intermediate and open position. The line α represents the meeting edges of the doors when in closed position; the lines a , a' represent the edges of the lower and upper doors respectively when in intermediate position; and the lines b , b' represent the edges of the upper and lower doors respectively when in extreme open position. I have applied numerals 10 and 11 to the links in this view and the numerals 6 and 7 to the levers, and have added to these numerals the letter a to designate their intermediate positions and the letter b to designate their position when the doors are open to their full extent. The arc of movement of the pivot connecting the lever 7 with the link 11, I have designated by the letter c , and the corresponding arc of movement of the pivotal connection between the lever 6 and the link 10, I have designated by the letter d . The arcuate movement of the pivotal connection of the link 11 with the upper

door, I have designated e , and the arc of movement of the pivotal connection between the link 10 and the lower door I have designated f . The pivotal connection of the doors with the door frame is indicated by the numerals 2, 3. Upon reference to the lower part of the diagram showing the movement of the lever and link connected to the lower door, it will be observed that during the first part of the opening movement of the door, the paths of movement of the pivotal connections at opposite ends of the link 10 converge, then intersect, and after their intersection, diverge. The proportions of the lever 6 and link 10 are such and the points of pivotal connection of the link 10 with the lever and with the door are so related that when the lower door has reached its fully open position the link 10 is in alignment with the lever 6, this latter position of these parts being indicated by the reference numerals 6^b and 10^b . I have shown the position 10^b of the link 10 at a slight angle to the lever 6 in order to make the illustration clear, but in practice and as actually constructed the link 10 falls into substantial alignment with the link 6 in the fully open position of the door. It will also be observed that as the lever 6 moves from the position designated 6 through the position 6^a to the position 6^b , the force transmitted from the lever through the link 10 to the door becomes less and less effective by reason of the rotation of the link from a position substantially normal to the lever to a position in alignment therewith, and it will further be apparent that the movement of the door cannot proceed beyond the position indicated by the numerals 6^b and 10^b . At this point the arcs d and f have diverged to an extent equal to the length of the link 10, and as continued movement could take place only by further divergence of these arcs which is prevented by the link 10 the doors are brought to a stop in the position corresponding to that indicated by the numerals 6^b and 10^b . By this means I have provided for the gradual retardation and stopping of the door movement, and have provided a cushioning effect that brings the door to rest without shock, and the means so provided are independent of the cushioning effect taking place by reason of compression of the air confined between the two pistons as above described. The gradual decrease in effectiveness of the force transmitted from the lever 6 through the link 10 to the door causes a diminution of the resultant force acting upon the door as it approaches the limit of its opening movement and hence the absolute arrest of the opening movement by the arrival of the parts at the position indicated by the numerals 6^b and 10^b is accomplished without shock.

A further advantage of the construction and operation last above described arises from the fact that any tendency of the lower door to rebound after arriving at its fully open position, is prevented not only by the weight of the lower door, but by the fact that any upward movement of the lower door at this time could take place only by causing a continued clockwise rotation of the lever 6 caused by continued clockwise rotation of the link 10, and such clockwise movement of the lever 6 is resisted by the downward pull thereby caused upon the link 16, which downward pull is opposed by the weight of the upper door.

The action above described in connection with the lower door also takes place in connection with the upper door, though to a lesser extent, as it will be observed from Figure 4, that in the extreme open position of the doors the link 11 is not in exact alinement with the lever 7. I found that sufficient cushioning effect is produced by so proportioning and arranging the parts connected to the lower door that the link 10 comes into alinement with the lever 6 when the doors are fully opened, and, of course, the cushioning effect applied to the lower door is transmitted to the upper door by reason of their interconnection between the levers and link.

It will be observed that the interconnection between the upper and lower doors is such that the weight of each door exerts an upward force upon the other door, thereby causing the doors to balance each other with the result that when left free to move under the force of gravity they will remain stationary in any position to which they are adjusted. In operation it sometimes becomes desirable to open the doors part way and to leave them in that position for a considerable time, as when a train is approaching a station and it is desired to abate the smoke. The means provided for this purpose are described and claimed in the Robinson Patent No. 1,492,896, above referred to, and I shall, therefore, herein introduce only a brief description thereof. Assuming that the doors are in the closed position shown in Figure 1, and it is desired to open them a short distance and to leave them in that position for some time, it simply is necessary to turn the valve 43, shown in Figure 5, a quarter turn clockwise thereby shutting off the supply of pressure to the space between the two pistons and establishing communication between that space and the atmosphere. The doors are thereby released from any force due to air pressure, the air between the pistons having been allowed to escape and the air on the outer side of the large piston being shut off by reason of the operating treadle being in its upper, normal, position.

By reference to Figures 1, 2 and 3, it will be observed that I have provided an operating handle 50 attached to the upper door above its hinge pivot 3. With the valve 43 adjusted as above described, the doors may be opened by manual operation of the lever 50 and the doors will remain in any position to which they are adjusted by reason of the fact that they are so connected as to counter-balance each other and are not subject to air pressure.

While I have shown an inwardly opening check valve in the duct 38-39-40-41 leading from the compressed air pipe 35 to the space between the two pistons, I have found that the use of this check valve may be dispensed with, ample cushioning effect upon the opening of the doors being obtained by the action of the levers and links above described. When the check valve is used, its effect is to confine the body of air between the two pistons, thereby causing this air to be subjected to pressure above that of the air supply when the pistons move to the left, to the position corresponding to the open position of the doors. When the check valve is removed, the space between the pistons is never subjected to air pressure above that of the main air supply except to the extent caused by the size of the duct 38-39-40-41 not permitting the backward flow of air toward the pipe 35 with sufficient rapidity to prevent some building up of pressure between the pistons when they move to the left. As above stated, I have found that sufficient cushioning effect may be obtained without the use of the check valve.

The doors will remain open as long as the treadle 37 is held depressed, thereby maintaining air pressure between the pistons and upon the outer side of the large piston. When the foot treadle is released and returns to its normally elevated position, communication is thereby established between the pipe 34 and atmosphere through the valve 36.

I effect the cushioning upon the closing of the doors in the manner described in the patents before referred to. Upon reference to Figure 5 it will be apparent that upon the movement of the piston 27 to the right, which is its movement in closing the doors, the air at the right-hand end of bore 25 at first escapes through branch 60 of duct 46 but that when piston 27 arrives opposite and obstructs branch 60 the remaining air in the end of the cylinder is entrapped and can escape only through the minute bleed opening 48 with the result that this entrapped air is compressed before it can escape thus cushioning the closing movement of the door.

What I claim as my invention is:

1. In a structure of the class described, a door supported on a pivot to move in the

plane of a door opening, a lever fulcrumed eccentrically of said door, a link, pivots connecting said link to said lever and door, the opening movement of said door being limited by the divergence of the arcuate paths of the pivots at the opposite ends of said link to an extent greater than the length of said link, and said link in the extreme open position of said door lying in alinement with said lever and extending from its pivotal connection with said lever toward the fulcrum of said lever.

2. In a structure of the class described, two doors movable toward and away from each other in a substantially vertical plane, door connecting members having pivotal connection with said doors, said connecting members causing the weight of each door to exert an upwardly acting force on the other door, said connecting members comprising levers and links, each of said links having pivotal connection with one of said levers and with one of said doors, the opening movement of said doors being limited by the divergence of the paths of movement of the pivots at opposite ends of one of said links to an extent greater than the length of said link.

3. In a structure of the class described, two doors movable toward and away from each other in a substantially vertical plane, door connecting members having pivotal connection with said doors, said connecting members causing the weight of each door to exert an upwardly acting force on the other door, said connecting members comprising levers and links, each of said links having pivotal connection with one of said levers and with one of said doors, the opening movement of said doors being limited by the divergence of the paths of movement of the pivots at opposite ends of one of said links to an extent greater than the length of said link, and means for applying power to said doors through said levers to open and close the same.

4. In a structure of the class described, two doors pivoted for movement toward and away from each other in a substantially vertical plane, door connecting members having pivotal connection with said doors, said connecting members causing the weight of each door to exert an upwardly acting force on the other door, said connecting members comprising levers and links, each of said links having pivotal connection with one of said levers and with one of said doors, the opening movement of said doors being limited by the divergence of the arcs of movement of the pivots at opposite ends of one of said links to an extent greater than the length of said link.

5. In a structure of the class described, two doors pivoted for movement toward and away from each other in a substantially ver-

tical plane, door connecting members having pivotal connection with said doors, said connecting members causing the weight of each door to exert an upwardly acting force on the other door, said connecting members comprising levers and links, each of said links having pivotal connection with one of said levers and with one of said doors, the opening movement of said doors being limited by the divergence of the arcs of movement of the pivots at opposite ends of one of said links to an extent greater than the length of said link, and means for applying power to said doors through said levers to open and close the same.

6. In a device of the class described, an upper and a lower door pivoted for movement parallel to the plane of a door opening and adapted to meet substantially midway of said opening, two levers having fixed fulcras, links each having pivotal connection at one end with one of said levers and at the opposite ends with said upper and lower doors respectively, said levers in the closed position of said doors lying between the meeting edges of said doors and the pivotal connections of said links with the doors, and a link having pivotal connection with said levers upon opposite sides of their fulcras.

7. In a device of the class described, an upper and a lower door pivoted for movement parallel to the plane of a door opening and adapted to meet substantially midway of said opening, two levers having fixed fulcras, links each having pivotal connection at one end with one of said levers and at the opposite end with said upper and lower doors respectively, said links in the closed position of said doors lying substantially normal to said levers.

8. In a device of the class described, an upper and a lower door pivoted for movement parallel to the plane of a door opening and adapted to meet substantially midway of said opening, two levers having fixed fulcras, links each having pivotal connection at one end with one of said levers and at the opposite ends with said upper and lower doors respectively, said links in the closed position of said doors lying substantially normal to said levers, said levers in the closed position of said doors lying between the meeting edges of said doors and the pivotal connection of said links with the doors, and a link having pivotal connection with said levers upon opposite sides of their fulcras.

9. In a device of the class described, an upper and a lower door pivoted for movement parallel to the plane of a door opening and adapted to meet on a substantially horizontal line substantially midway of said opening, two levers having fixed fulcras, links each having pivotal connection at one end with one of said levers and at the op-

posite ends with said upper and lower doors respectively, said levers in the closed position of said doors lying between the meeting edges of said doors and the pivotal connections of said links with the doors, a link having pivotal connection with said levers upon opposite sides of their fulcra, a fluid-operated cylinder above said door opening and having its axis substantially horizontal, and a piston in said cylinder, said piston being linked to said levers.

10. In a device of the class described, an upper and a lower door pivoted for movement parallel to the plane of a door opening and adapted to meet on a substantially horizontal line substantially midway of said opening, two levers having fixed fulcra, links each having pivotal connection at one end with one of said levers and at the opposite ends with said upper and lower doors respectively, said links in the closed position of said doors lying substantially normal to said levers, a link having pivotal connection with said levers on opposite sides of their fulcra, a fluid-operated cylinder above said door opening and having its axis substantially horizontal, and a piston in said cylinder, said piston being linked to said levers.

cylinder, said piston being linked to said levers.

11. In a device of the class described, an upper and a lower door pivoted for movement parallel to the plane of a door opening and adapted to meet on a substantially horizontal line substantially midway of said opening, two levers having fixed fulcra, links each having pivotal connection at one end with one of said levers and at the opposite ends with said upper and lower doors respectively, said links in the closed position of said doors lying substantially normal to said levers, said levers in the closed position of said doors lying between the meeting edges of said doors and the pivotal connection of said links with the doors, a link having pivotal connection with said levers upon opposite sides of their fulcra, a fluid-operated cylinder above said door opening and having its axis substantially horizontal, and a piston in said cylinder, said piston being linked to said levers.

Signed at Chicago, Illinois, this 9th day of June, 1924.

JAY G. ROBINSON.
